UNITED STATES PATENT OFFICE.

HENRY F. FISHER, OF LOS ANGELES, CALIFORNIA.

BOW-GUIDE.

1,353,036.

Specification of Letters Patent. Patented Sept. 14, 1920.

Application filed February 25, 1920. Serial No. 361,349.

To all whom it may concern:

Be it known that I, HENRY F. FISHER, a citizen of the United States, residing at Los Angeles, in the county of Los Angeles and 5 State of California, have invented new and useful Improvements in Bow-Guides, of which the following is a specification.

This invention relates to musical instruments and has for its object to provide an 10 improved guide attachable to the bodies of violins for the purpose of guarding or guiding the bow in its movement across the strings, and has for its further object to provide a device of this character that is 15 simple, inexpensive, substantial, durable, and that may be readily applied and adapted to violins having transverse body portions of different diameters or transverse dimensions, and the invention consists of the construction and details an embodiment of 20 which is illustrated in the accompanying drawings and described and claimed herein.

Figure 1 is a plan view of a violin to which the invention is applied.

25 Fig. 2 is an edge view of the violin and applied guide.

Fig. 3 is a section on line 3—3 of Fig. 1 showing the improved guide in elevation.

The improved guide, in its illustrated embodiment, comprises right and left-hand bracket members 2 and 3 respectively that may be, and preferably are, made of flat strip material as metal; the right-hand bracket having a downwardly extending 35 curved arm 2' with a hook 2^a on its lower end to be passed beneath the over-hanging bead of the face or top board 4 of a violin generally indicated at V.

The body embracing face of the hook 2^a 40 is preferably provided with a protecting or cushioning strip 5 to prevent marring the finish of the violin and also to prevent undesirable vibration of the parts. This bracket 2 has an upwardly extending arm 2^b 45 of suitable length that is provided with a threaded aperture 6 adjacent its upper end, and just below the same is provided with a plane aperture through which freely passes a tightening screw 7 the opposite threaded portion of the upwardly extending arm 3^b of 50 suitable length that is provided with a threaded aperture 6 adjacent its upper end, and just below the same is provided with a plane aperture through which freely passes a tightening screw 7 the opposite threaded portion of the upwardly extending arm 3^b of the bracket 3, this latter having a downwardly extending padded hook 3^a to embrace the opposite edge of the violin body. 55 Transversely connecting the upper por-

tions of the arms 2^b and 3^b is a spacing screw or rod 8, one threaded end of which engages the threaded aperture 6 of the bracket arm 2^b while the opposite threaded end of the spacing rod 8 engages a complementary threaded aperture in the arm 3^b.

From this it will be seen that by turning the spacing rod 8 in either direction the rod will effect the contraction or separation of the bracket arms 2 and 3 to enable their hooks to be brought into engagement with the edge beads of the top panel 4 of the violin. When having been so adjusted the lower ends of the arms 2 and 3 can be drawn into tight embrace with the edge beads by 70 means of screw 7 so that the arms will be substantially maintained in an upright position.

One or the other of the arms, in this case the arm 3, is provided with an upwardly 75 extending and inwardly directed guide or guard part 9 which in this case is shown as produced by twisting the upper portion of the arm 3^b as at 10 to bring the flat plane of the strip transverse to the longitudinal 80 axis of the violin; the guard or guide part 9 when so arranged projecting such distance above the strings S of the violin to clear the same and to be so located as to support the bow bar while the hairs of the bow are resting on the strings. Preferably the guide or overhanging part 9 is provided with a cushioning jacket such as a leather or other suitable thimble 11.

From the above it will be seen that the 90 device is adapted to be placed across the body of the violin on such a transverse line as may be desired in a position between the bridge B and the end of the finger board F and so that when the player is running the 95 bow, not shown, across the strings the tendency of the bow to shift toward the bridge will be overcome.

It is understood that the threads on the 100 spacing rod 8 may be right and left-hand on opposite ends to facilitate the adjustment of the brackets.

Various changes may be made without departing from the spirit of my invention as claimed.

I claim:

1. A bow guide for violins, or the like, comprising a pair of connected relatively adjustable bracket members with means for drawing said members toward one another 110

for clamping the same to the body of a violin, one of the bracket members having a guide forming part engageable by the bow.

2. A bow guide for violins including a pair of adjustable bracket members, the outer end of said members being formed to engage the side edges of the top of the violin, arms upstanding from the inner end of said brackets, means for engaging said arms to draw their outer ends firmly into engagement with the side edges of the top of the violin, the upper end of one of said arms being bent inwardly and downwardly above the strings to form a bow guide.

15 3. A bow guide for violins comprising a pair of brackets with hook members to be fitted to the opposite edge beads of the bouts; a spacing member for adjusting the brackets; a locking or clamping member for drawing said brackets toward one another; and a guide part for engagement of the bow.

4. A bow guide for violins including a pair of adjustable brackets, the outer ends of said brackets being formed to engage the side edges of the top of the violin, arms comprising strips upstanding from the inner end of said brackets, with the width of said strips extending parallel to the longitudinal axis of the violin, means for engaging said arms to draw their outer ends firmly into engagement with the side edges of the top of the violin, one of said arms being twisted at right angles to present the width thereof for contact with the bow.

35 5. A bow guide for violins including a

pair of adjustable brackets, the outer end of said brackets being formed to engage the side edges of the top of the violin, arms upstanding from the inner end of said brackets, a screw extending through the base of one of said arms and engaging the base of the other arm for drawing the outer ends of said brackets into engagement with the side edges of the top of the violin, one of said arms being bent inwardly and downwardly to form a bow guide.

6. A bow guide for violins including a pair of adjustable brackets, the outer end of said brackets being formed to engage the side edges of the top of the violin, arms upstanding from the inner end of said brackets, a screw extending through the base of one of said arms and engaging the base of the other arm, a screw having oppositely inclined threads at its ends engaging said upstanding arms respectively, one of said arms being bent inwardly and downwardly to form a bow guide.

7. A bow guide for violins or the like, comprising a pair of bracket members relatively adjustable and arranged to be clamped to the body of the violin, and arms comprising strips upstanding from the inner end of said brackets, one of said arms being twisted at right angles to present the width thereof for contact with the bow.

In testimony whereof I have signed my name to this specification.

HENRY F. FISHER.
